(57) **CLAIM**

The ornamental design for an insect trap, as shown and described.

DESCRIPTION

FIG. 1 is a perspective view of an insect trap showing an embodiment of my new design.

FIG. 2 is a side view thereof;

FIG. 3 is an opposite side view thereof;

FIG. 4 is a rear view thereof;

FIG. 5 is a front view thereof;

FIG. 6 is a top view thereof; and,

FIG. 7 is a bottom view thereof.

The portions shown in broken lines form no part of the claimed design.
